(Cl. D47—7)

To all whom it may concern:

Be it known that I, Saul Sigel, a citizen of the United States, residing at Manchester, in the county of Hillsborough, and State of New Hampshire, have invented a new, original, and ornamental Design for a Stocking, of which the following is a specification, reference being had to the accompanying drawing, forming part thereof.

Figure 1 is a side elevation of a stocking, showing my new design.

Figure 2 is a fragmentary rear elevation of the same.

The characteristic feature of my design resides in the combination on a stocking of a heel and splice decoration of the configuration disclosed suggestive of the spire of a minaret.

I claim:

The ornamental design for a stocking, as shown and described.

SAUL SIGEL.
